UNITED STATES PATENT OFFICE.

JOSEPH S. PECKER, OF PHILADELPHIA, PENNSYLVANIA.

WARP-KNITTING MACHINE.

Application filed January 12, 1922. Serial No. 528,776.

To all whom it may concern:

Be it known that I, JOSEPH S. PECKER, a citizen of the United States, residing at Philadelphia, in the county of Philadelphia and 5 State of Pennsylvania, have invented new and useful Improvements in Warp-Knitting Machines, of which the following is a specification.

The invention relates to a double rib knitting machine in which pattern work, such as embroidery, edging used in trimming under- 10 wear or curtains, or various patterns of neck- ties, can be made.

Heretofore in a knitting machine of this 15 character one of the essential features has been to maintain the needle bar in a perfectly horizontal plane. The only points at which a needle bar can be supported in such a knitting machine are at the ends of the 20 needle bar. It has been the practice to suspend this needle bar, usually an angle iron bar, on two short bearings, and in order to give the necessary rise and fall to the needle bar, two cams and two sets of levers have 25 been employed to operate on the needle bar supports.

If the adjustments of the levers at both 30 ends of the needle bar are not absolutely true, or if the cam surfaces at both ends of the machine are not absolutely alike, or if 35 they are set at a fraction of an angle different, it will cause the bearings at the ends of the machine to bind and will result in one end of the needle bar being lifted higher 40 than the other. This cross bar or needle bar in its downward movement must be pulled down either by springs or weights, or must depend upon its own weight to overcome the friction in the bearings. Also after constant

45 operating of such machine one of the levers may give way at the adjustment points and it will lift the needle bar against a binding friction in the bearings and in the downward movement of the needle bar will tend to stick in bearings and the springs or weights will be insufficient to return the needle bar to the downward limit of its movement. The 50 result will be a general smashing up of the needles and the spoiling of the fabric at that point.

The object of the present invention is to 55 improve the construction of such knitting machines and to provide a simple, practical and efficient construction which will be strong and durable and comparatively in-

expensive and capable of imparting the rise and fall motion to the needle bar and of eliminating all possible shake and vibration which would cause faulty work and adapted to also obtain a higher speed of operation 60 than has heretofore been possible with machines of this character.

With these and other objects in view the invention consists in the construction and novel combination and arrangement of parts 65 hereinafter fully described, illustrated in the accompanying drawings and pointed out in the claims hereto appended, it being understood that various changes in the form, proportion and minor details of construction, 70 within the scope of the claims, may be resorted to without departing from the spirit or sacrificing any of the advantages of the invention.

In the drawings, in which like characters 75 of reference designate corresponding parts in the several views:

Figure 1 is a vertical sectional view of a knitting machine embodying the present invention, some parts being omitted.

Figure 2 is a front elevation of the same, partly in section.

Figure 3 is a plan view, partly in section.

Figure 4 is a detail view of a portion of 85 one of the rocking levers illustrating the adjustable connection between the same and the adjustable link.

Figure 5 is a detail sectional view illustrating the construction for adjustably 90 mounting the needle bar.

Figure 6 is a plan view of the same.

Figure 7 is a sectional view of one of the cams.

In the accompanying drawings, in which 95 is illustrated the preferred embodiment of the invention, the frame of the knitting machine comprises standards 1 tied together by cross horizontal bars 2 and provided at the upper and lower portions with vertically aligned top and bottom guide ways 3 for the reception of vertically reciprocating staffs 4 and 5. The upper and lower guide ways 3, which in practice are spaced as far apart as the construction of the machine 100 will permit in order to afford a firm construction and prevent any possibility of shake or vibration of the vertically reciprocating staffs 4 and 5 or variation in the true vertical motion of the same at either end 110

of the machine, consist of brackets bolted or otherwise secured to the standards of the upper and lower portions thereof, as clearly illustrated in Figure 2 of the drawings, and 5 provided with removable face plates 3^a, which detachably retain the vertically reciprocating staffs in guiding grooves 3^b of the brackets. The guiding grooves 3^b of the brackets or guide ways 3 are arranged 10 in pairs to accommodate the pairs of vertically reciprocating staffs 4 and 5, as clearly shown in Figure 3 of the drawings, and the said staffs 4 and 5 carry needle bars 7, which are provided with the usual knitting 15 needles 6.

The up and down motion is imparted to the needle bar 7 by cams 8 mounted on the main operating shaft 9 of the machine and actuating rocking levers 10, which are connected by the link connections with horizontal bars 14 which tie or connect the vertically reciprocating staffs at opposite sides of the machine with each other. The rocking levers 10 are arranged centrally of the 20 machine and are connected with the tie bars 14 centrally thereof and are fulcrumed intermediate of their ends on a shaft or pivot 15, which is supported in spaced centrally arranged brackets 16 and 17. The 25 tie bars 14 which connect the staffs 4 and 5 are secured to the same by bolts 18 or other suitable fastening means, and the needle bars 7 are secured to the upper ends of the staffs by bolts 19.

Each rocking lever 10 is provided at its 30 inner end with a longitudinal slot 20, in which is mounted a sliding block 21 carrying a pin or pivot 22 and secured in its adjustment by a clamping screw 23. The 35 sliding block 21 is adjustable longitudinally of the slot 20 by an adjusting screw 24, journaled in a suitable bearing 10^a of the rocking lever and engaging a threaded bore 21^a in the longitudinal sliding block, 40 whereby when the clamping screw 23 is loosened and the adjusting screw 24 is rotated the slideable block 21 will be moved inwardly or outwardly with respect to the end of the lever and after an adjustment 45 has been effected the clamping screw 23 may be tightened to securely clamp the sliding block in its adjustment so that there will be no liability of the rocking motion of the parts affecting the adjustment of the sliding block. The link connection between the 50 rocking lever and the tie or connecting bar 14 comprises upper and lower sections 11 and 12, and the centrally connecting member 13, which is in the form of a right and left hand threaded adjusting screw. The 55 upper and lower sections 11 and 12 are in the form of yokes, the lower section or yoke 11 straddling the rocking lever and having its side portions pivoted to the sliding block 60 by the pin or pivot 22. The upper section 65

or yoke 12 straddles a lug 25 of the cross or connecting bar 14 and is pivoted to the same by a pin or pivot 26. The upper and lower yokes or sections 11 and 12 are provided with threaded openings or sockets 11^a, 70 which are engaged by the right and left hand threaded portions of the central adjusting screw or member 13 and the latter is provided with a centrally arranged polygonal portion adapted to receive a wrench or 75 other suitable tool for rotating the adjusting screw 13 to vary the effective length of the link or connection between the rocking lever and the cross or tie bar 14 and the distance between the rocking lever and the needle 80 bar. Lock nuts 11^b are provided for securing the adjusting screw in its adjustment. The upper sections 12 of the link connections have L-shaped offset portions disposed in vertical overlapping relation to arrange 85 them centrally beneath the needle bars.

Each rocking lever is provided at its outer end with a roller 27 which runs in a cam groove 8^a in the cam 8, and the said groove, which forms a track for the roller, tends 90 to hold the lever in a firm position at any part of the cam and thereby prevents lost motion and eliminates the necessity of employing supplementary spring tensions or weights to prevent such lost motion. 95

The needle bar 7 is provided at each end with a square hole 28 to receive the vertically reciprocating staffs 4 and 5 and the needle bar is supported upon a shoulder 29 of the staff formed by recessing the latter, 100 as clearly illustrated in Figure 5 of the drawings. The reciprocating staffs are rectangular in cross section and the recess which forms a shoulder or seat 29 is provided with an inclined wall or face 29^a to fit the inclined face of a vertically adjustable wedge 30 interposed between the face 29^a of the vertically reciprocating staff and adjustable by means of a screw 31. The wedge 30 is provided with slots 32 through which the bolts 110 19 pass for securing the needle bar to the vertically reciprocating staff and the adjusting screw 31, which is mounted in a threaded opening or socket 33 of the said staff, is provided above the upper end of the same 115 with a head which fits in a horizontal groove 34 in the adjacent face of the wedge 30. The screw is capable of vertical adjustment to raise and lower the wedge 30 and the wedge 30 will effect a horizontal adjustment of the 120 needle bar 7. The screws 19 clamp the needle bar in its adjustment and the adjusting means of the needle bar is adapted to maintain a square seat of the needle bar on the ends of the staffs. 125

By connecting the links of the rocking levers with the cross or tie bars 14 at the centers thereof the mechanism for imparting a rise and fall motion to the needle bars is applied at the center of gravity or center of 130

support of the needle bars and the brackets 17 support the main operating shaft at opposite sides of the center of the machine and take out all vibration from the main drive or 5 operating shaft and by this construction the rocking levers, links and cams are arranged in close proximity to one another. The rocking levers permit of a fine adjustment of the link connection and at the same time 10 provide for a quick and positive adjustment of the pivotal connections between the rocking levers and the links. Also the long staffs are provided for guiding the needle bars in their movements.

15. What is claimed is:

1. A knitting machine including a frame having top and bottom guides, long staffs extending from the top to the bottom of the frame and reciprocating vertically in the 20 guides, a needle bar carrier by the staffs, and mechanism for imparting a rise and fall motion to the needle bars.

2. A knitting machine including a frame having top and bottom guides, long staffs 25 extending from the top to the bottom of the frame and reciprocating vertically in the guides, a needle bar carried by the staffs, and mechanism centrally connected with the needle bar at a point intermediate of the ends 30 of the staffs for imparting a rise and fall motion to the same.

3. A knitting machine including a frame, guides secured to the sides of the frame, long staffs arranged in pairs and extending from 35 the top to the bottom of the frame and reciprocating vertically in said guides, and mechanism for imparting a rise and fall motion to the needle bars connected with the same centrally thereof.

40. 4. A knitting machine including a frame, brackets located at the top and bottom of the frame and provided with guide grooves and having inner removable face plates covering the said grooves, staffs extending from the top to the bottom of the frame and reciprocating vertically in the guide grooves of the brackets, a needle bar carried by the staffs, and means for imparting a rise and fall motion to the needle bar, said means being centrally arranged and located intermediate of the ends of the staffs.

5. A knitting machine including a frame, brackets located at the top and bottom of the frame and secured to the sides of the same 55 and provided with guide grooves arranged in pairs, long staffs square in cross section extending from the top to the bottom of the frame and reciprocating vertically in the said grooves, needle bars carried by the staffs, and means for imparting a rise and fall motion to the needle bars.

6. A knitting machine including vertically reciprocating staffs having horizontal shoulders forming seats, guide ways for the staffs. 65 and a needle bar adjustable horizontally on

the seats, means for moving the needle bar inwardly and outwardly, and means for securing the needle bar in its adjustment.

7. A knitting machine including vertically reciprocating staffs having shoulders forming seats, guide ways for the staffs, a needle bar arranged on the said seats and provided with openings receiving the staffs, means for moving the needle bar horizontally on the seats, and means for securing the needle bar 75 in its adjustment.

8. A knitting machine including vertically reciprocating staffs having shoulders forming seats, guide ways for the staffs, a needle bar arranged on the said seats and provided with openings receiving the staffs, and adjustable wedges interposed between the needle bar and the staffs for adjusting the needle bar horizontally on the seats.

9. A knitting machine including vertically reciprocating staffs having shoulders forming seats, guide ways for the staffs, a needle bar arranged on the said seats and provided with openings receiving the staffs, wedges interposed between the needle bar and the 90 staffs, and vertical adjusting screws mounted on the staffs and connected with the wedges for adjusting the needle bar horizontally on the seats.

10. A knitting machine including vertically reciprocating staffs having shoulders forming seats, guide ways for the staffs, a needle bar arranged on the said seats and provided with openings receiving the staffs, wedges interposed between the needle bar and the 95 staffs, and horizontal screws piercing the staffs and connected with the needle bar for securing the same in its adjustment.

11. A knitting machine including staffs extending from the top to the bottom of the frame, means for guiding the same, a needle bar carried by the staffs, and central mechanism for imparting a rise and fall motion to the needle bar, located between the staffs intermediate of the ends thereof comprising 100 a rocking lever, a cam for actuating the rocking lever, and a link connection between the rocking lever and the needle bar.

12. A knitting machine including needle bars, means mounted on the sides of the frame for guiding the same and including vertical staffs extending from the top to the bottom of the frame, centrally arranged mechanisms for imparting a rise and fall motion to the needle bars, located between 115 the sides intermediate of the ends thereof comprising rocking levers, link connections having offset centrally arranged upper ends connected with the needle bars beneath the centers of the same, and means for actuating the rocking levers.

13. A knitting machine including a needle bar, means mounted on the sides of the frame for slidably mounting the same for up and down movement and including ver- 120

- 65
 tical staffs extending from the top to the bottom of the frame, and centrally arranged mechanism for imparting a rise and fall movement to the needle bar, located between
 5 the staffs intermediate of the ends of the same comprising a rocking lever, a link connection between the rocking lever and the needle bar, having a pivot adjustable longitudinally of the lever, and means for actuating the lever.
- 10 14. A knitting machine including a needle bar, means for slidably mounting the same for up and down movement, said means including guides mounted on the sides of the frame and vertical staffs extending from the top to the bottom of the frame and slidably in the said guides and centrally arranged mechanism for imparting a rise and fall movement to the needle bar, located between
 15 20 the staffs intermediate of the ends thereof comprising a rocking lever having a longitudinal slot, a block slideable in and adjustable along the slot and provided with a pivot, a link connection between the pivot and the needle bar, and means for actuating the rocking lever.
- 25 15. A knitting machine including a needle bar, means for slidably mounting the same for up and down movement, said means including guides mounted on the sides of the frame and vertical staffs extending from the top to the bottom of the same and slideable in the guides and centrally arranged mechanism for imparting a rise and fall movement to the needle bar, located between the staffs intermediate of the ends of the same comprising a rocking lever having a longitudinal slot, a block slideable in and adjustable along the slot and provided with a pivot, a link connection between the pivot and the needle bar, a longitudinal adjusting screw mounted on the lever and connected with the block, a clamping screw also mounted on the lever and engaging the said block, and means for actuating the lever.
- 30 16. A knitting machine including a needle bar, means for slidably mounting the same for up and down movement, said means including guides mounted on the frame at the top and bottom thereof and staffs extending from the top to the bottom of the frame and slideable in the guides and centrally arranged mechanism for imparting a rise and fall movement to the needle bar, located between the staffs intermediate of the ends thereof comprising a rocking lever, a link connection between the rocking lever and the needle bar, composed of upper and lower sections and an intermediate right and left hand threaded connecting screw for varying the effective length of the link, and means for actuating the lever.
- 35 17. A knitting machine including a needle bar, means for slidably mounting the same for up and down movement, said means including vertical staffs extending from the top to the bottom of the frame and slidably mounted on the sides of the same and mechanism arranged to impart a rise and fall movement to the needle bar, located between
 40 45 the staffs intermediate of the ends thereof comprising a rocking lever, means for connecting the rocking lever with the needle bar, and a cam having a groove for actuating the rocking lever with a true and steady motion.
- 50 18. A knitting machine including a frame, vertically reciprocating staffs guided at opposite sides of the frame and extending from the top to the bottom of the same, needle bars carried by the staffs, tie bars connecting the staffs intermediate of the ends thereof, centrally arranged bearing brackets, an operating shaft journaled in the bearing brackets, a pair of rocking levers fulcrumed between the bearing brackets and connected at their inner ends with the said tie bars, and cams mounted on said shaft located at the outer ends of the levers for actuating the same.
- 55 19. A knitting machine including a frame, vertically reciprocating staffs guided at opposite sides of the frame and extending from the top to the bottom of the same, needle bars carried by the staffs, tie bars connecting the staffs intermediate of the ends of the same, centrally arranged bearing brackets located between said staffs, an operating shaft journaled in the bearing brackets, a pair of rocking levers fulcrumed between the bearing brackets, link connections between the rocking levers and the tie bars, said link connections having offset ends located centrally beneath the needle bars, and means located at the outer ends of the rocking levers for actuating the same.
- 60 20. A knitting machine including a frame, vertically reciprocating staffs guided at opposite sides of the frame and extending from the top to the bottom of the same, needle bars carried by the staffs, tie bars connecting the staffs intermediate of the ends of the same, centrally arranged bearing brackets located between the staffs, a driving or operating shaft journaled in the bearing brackets, a pair of rocking levers fulcrumed between the bearing brackets, link connections between the rocking levers and the tie bars, said link connections having offset ends located centrally beneath the needle bars, cams located at the outer ends of the rocking levers and provided with cam grooves, and means carried by the rocking levers for engaging the cam grooves.
- 65 70 75 80 85 90 95 100 105 110 115 120 125
 In testimony whereof I have hereunto set my hand.
